UNITED STATES PATENT OFFICE.

ANNE AGNES AVERY, OF HOLLYWOOD, CALIFORNIA.

DESIGN FOR A STATUETTE.

Application filed April 12, 1923. Serial No. 5,791. Term of patent 3; years.

To all whom it may concern:

Be it known that I, ANNE AGNES AVERY, a citizen of the United States, residing at Hollywood, in the county of Los Angeles and State of California, have invented a new, original, and ornamental Design for Statuettes, of which the following is a specification, reference being had to the accompanying drawing, forming part thereof.

Fig. 1 is a front elevation of a statuette, showing my new design.

I claim:

The ornamental design for a statuette, as shown.

ANNE AGNES AVERY.
